UNITED STATES PATENT OFFICE.

ENGLAND J. BARKER, OF CHICAGO, ILLINOIS.

EXTRACTING MECHANISM FOR AUTOGRAPHIC REGISTERS.

1,284,557.

Specification of Letters Patent. Patented Nov. 12, 1918.

Application filed March 27, 1916. Serial No. 86,867.

To all whom it may concern:

Be it known that I, ENGLAND J. BARKER, a citizen of the United States, residing at Chicago, in the county of Cook and State of Illinois, have invented new and useful Improvements in Extracting Mechanism for Autographic Registers, of which the following is a full, clear, and exact description.

My invention relates to autographic registers, and particularly to mechanism for facilitating the removal of the paper records therefrom.

The continuous paper rolls used in registers of the type to which my improvements are applied have forms printed thereon that are of a given length and follow one another in close succession throughout the length of the roll. Some of these forms are used in the salesroom, some in the shipping department and some in the accounting room, and they vary in length according to the use to which they are put and according to the ideas of the different institutions using them. Heretofore these forms, after they had been written upon, were removed by grasping their forward edges and pulling them out by hand and the judgment of the operator was relied upon to determine how far they should be pulled out and the point at which they should be torn off, or appliances were employed to gage the predetermined length of paper it was desired to tear off, and when such appliances were employed a separate machine was used for each length of form, or machines were used that had "pull-out" mechanism that could be adjusted to extract a predetermined length of paper. The paper used in these machines has one or more holes punched in each form printed thereon to enable them to be filed away either upon filing spindles or the posts of loose-leaf binders, and these punched holes are located near their advanced edge and occupy the same position relative to the printed matter in each form.

The object of my invention is to provide means that engage these punched holes when the advanced edge of the forms reach the withdrawal end of the register and utilize these holes to measure the length of the web of paper to be extracted from the same, and thus enable the paper to be torn off on the tearing-blade located at the discharge end of the machine always at the same point relative to the printed matter on each form. It

is also an object of my invention to so manipulate the pins that engage said punched holes that they automatically withdraw therefrom after the paper strip has been advanced to the grasping position, and remain out of engagement with the strips until the means supporting the same has automatically returned to its original position, at which position they automatically enter and engage the punched holes of the next following form when the pulled out form is in position to be torn off. These and other objects I accomplish by the means herein-after fully described, and as particularly pointed out in the claims.

In the drawings:

Figure 1 is an end view of the upper half of the end portion of an autographic register showing my improvements applied thereto.

Fig. 2 is a longitudinal section taken on dotted line 2-2, Fig. 1.

Fig. 3 is a longitudinal section taken on dotted line 3-3, Fig. 1.

Fig. 4 is a longitudinal section taken on dotted line 4-4, Fig. 1.

Fig. 5 is a longitudinal section similar to that shown in Fig. 4, showing the change in position of the movable parts.

Fig. 6 is a horizontal section of the discharge end portion of said register taken on dotted line 6-6, Fig. 1, looking in the direction indicated by the arrows.

Fig. 7 is a similar view of the broken away discharge end thereof showing the positions of the extracting elements when at the limit of their forward movement.

My invention relates only to mechanism located at the discharge end of an autographic register.

Referring to the drawings, A, A, represent the side-frames of the upper section of such register, B the horizontally disposed platen the side edges of which are secured to and connect the side-frames near their upper edges, and C the usual cover, which latter, in view of the fact that my improvements do not affect the same, is not thoroughly illustrated in said drawings.

The discharge end of the platen is fore-shortened and terminates a suitable distance back of the forwardmost portions of the vertical end edges of the side-frames, and between the forward transverse edge of the platen and the transverse vertical plane of

the forwardmost portion of said side-frames, a transversely disposed flat plate D is placed, the upper surface of which is in the same horizontal plane as that of said platen 5 and constitutes a movable extension of the same, substantially as hereinafter set forth. The ends of this extension-plate D overlap the upper edges of the side-frames, but are not connected thereto, and at suitable points 10 between its ends and its center of length it is mounted upon and secured to the forward ends of corresponding longitudinally disposed flat metal bars a, a, that extend back under the platen a suitable distance and are 15 held in slidable contact therewith by screws c, c, that are tapped into the platen and extend down through longitudinally elongated slots b, b, in said bars, substantially as shown.

20 Arranged above and suitably separated from extension-plate D is a transverse tearing-blade E, which has its ends supported upon suitable blocks resting upon and secured to the ends of said extension-plate.

25 The web of paper after it has passed over the platen is threaded between extension-plate D and tearing-blade E, and when the forms thereon are pulled out of the register until the filing holes thereof come between 30 said plate and blade vertically disposed pegs F automatically move up through openings in said plate and blade and pass through said filing-holes. There are, preferably, only two of these pegs, and these are, 35 respectively, located between the center of length of the extension-plate and the ends thereof. The lower ends of pegs F are secured in and supported by the forward ends of flat longitudinally disposed steel springs 40 d, d, whose rear ends extend back under the platen a suitable distance and are secured in any suitable manner to a flat cross-bar e, which latter connects and has its ends secured to strips a, a.

45 The extension-plate is kept at the limit of its rear movement in contact with the forward edge of the platen by means of a coil contraction-spring f, one end of which is secured to the center of length of cross-bar e, and the other end of which is secured to a suitable pin f' secured to and depending from plate B, as shown in Fig. 6 of the drawings. In order to move the extension-plate forward so as to extract the paper 50 from the register, as will hereinafter be more fully explained, bars a, a, are provided with depending arms G that consist of inverted L-shaped bars the horizontal portions of which are secured to the underside of said bars. These arms G are engaged by anti-friction rollers g journaled in the ends of arms H that are secured to and project upward and forward from a transverse rock-shaft I, the ends of which are journaled in 55 side-frames A and one end of which extends

through its bearings and is provided with a suitable crank J by means of which it is rocked.

This rock-shaft I has a coil spring h surrounding it near one side-frame whose ends are, respectively, secured to said side-frame and said shaft. The object of this spring h is to keep shaft I normally at the limit of its rearward movement, which latter is determined by means of an arm j secured to 75 and depending from the end of said shaft opposite spring h, which normally engages the lower end of a segmental flange k projecting laterally inward from the adjacent side-frame of the register. The forward 80 movement of rock-shaft I is limited by the engagement of an upward extension K of arm j the end of which is adapted to engage the rear end of a gage-screw L tapped rearward through said flange.

85 After the extension-plate has reached the forward limit of its movement the continued movement of crank J and rock-shaft I causes a pin 30, projecting forward therefrom at about its center of length to engage the 90 lower shoulder 8 of a recess 9 made in the adjacent side edge of the boss 10 of an arm 11 loosely mounted on said shaft. This arm is stationary during the first part of the forward movement of the shaft, but when 95 pin 30 engages shoulder 8 it is moved forward during the remainder of the movement of the same. The upper end 12 of arm 11 terminates a short distance below the platen and has a transverse dove-tail groove made 100 in its extremity that is engaged by a transverse flange 13 projecting down from a longitudinally reciprocable slide 14 consisting of a longitudinally disposed flat strip of metal which is held in alining engagement 105 with the underside of the platen by the head of a screw 15 that passes through a longitudinally elongated slot in said slide and is tapped into said platen.

110 The forward end of said slide terminates in a transverse wedge 16 the under beveled side of which extends downward, and the forward knife edge of said wedge, when the slide is at the rear limit of its movement, slightly overlaps the rear edge of the 115 center of length of a bridge 16a. Bridge 16a consists of a transverse flat strip of metal which is supported by and secured to the front end of the longitudinal flat springs g, g, whose rear ends are secured to the 120 underside of the platen, and the ends of said bridge overlie springs d, and when arm 11 moves forward it moves the slide forward, and wedge 16 of the latter thrusts in between the underside of the platen and bridge 125 16a and forces springs d and pegs F, F, downward below the upper surface of the extension-plate while permitting said spring to move longitudinally when the extension-plate moves. The withdrawal of pegs F, F, 130

from the holes in the paper enables the operator to reach under the extension-plate with his fingers and grasp the forward edge of the paper and pull the last form out—the 5 center of length of the forward edge of said extension-plate being recessed or cut away, as at 17, to facilitate this being done.

Immediately over the front edge of the platen is a superposed transverse bar 18 10 which has its ends resting upon and secured to the upper edges of the side-frames and is separated from the same a short distance to accommodate the passage of the paper under it. The center of length of the forward edge 15 of the platen is recessed, as at 19, to permit the upper horizontal edge of a flat tension-blade 20 to pass upward therethrough. This blade is transversely disposed and its lower edge is rolled into a knuckle 21 that is 20 loosely mounted upon a stationary shaft 22, which latter has its ends secured in the side-frames of the register. This tension-blade inclines slightly forward from shaft 22 when in its normal position, and it is kept at the 25 limit of its rearward movement by a wire spring 23, the central straight stretch of which extends longitudinally in front of the blade next its knuckle 21, and the end portions of which are coiled around said shaft 30 and have their extremities suitably attached thereto.

As hereinbefore stated, the web of the paper is passed over the platen and between bar 18 and the forward end of the platen 35 and then between extension-plate D and tearing-blade E. In order to permit the threading of the web of paper between said extension-plate and tearing-blade, however, pegs F must be withdrawn downward 40 through the tearing-blade and extension-plate without interfering with the movement of rock-shaft I or said extension-plate. This I accomplish by providing boss 10 of arm 11 with a downwardly projecting finger-grasp 24 and by mounting upon shaft I alongside of said arm, and between the same and a collar 35, a coil expansion spring 25. By grasping finger-grasp 24 and pushing it rearwardly arm 11 will move forward 45 independently of shaft I, and owing to the engagement of its upper grooved end 12 with flange 13, will move said slide forward and force wedge 16 on the forward end thereof in between bridge 16^a and the under- 50 side of the platen and force the forward ends of springs d, d, and pegs F downward out of the filing holes of the paper. The lower end of the inclined portion of wedge 16, next flange 13, is provided with a flat 55 horizontally disposed shoulder 27, and when the slide reaches the forward limit of its movement this shoulder overlaps bridge 16^a and holds it down, and as said arm 11 moves forward it overcomes the resistance of pin 60 30, rock-shaft I, et cetera, and, owing to

the bevel given the upper shoulder α of recess 9, moves toward and compresses springs 25 on said shaft I, which holds arm 11 stationary while permitting shaft I to move toward the limit of its rearward movement. 70

When the webs of the paper have been properly threaded between the extension-plate and the tearing-blade, arm 11 is moved to the rear independently of shaft I and pegs F automatically move upward and 75 bear against the underside of the web or webs of paper and when the paper has been drawn forward out of the register sufficiently to bring the filing-holes in the paper in vertical alinement with pegs F, the latter 80 will automatically shoot up through the same. When it is desired to extract the form on the platen next the discharge end of the register, shaft I is rocked through the medium of crank J, and the extension-plate and 85 tearing-blade move forward with the webs of paper held between them by pegs F, the paper is drawn forward until screws e reach the rear limit of slots b in bars a whereupon the forward movement of the said plate 90 and blade cease, and the continued forward movement of rock-shaft I causes arm 11 to move forward and the wedge to engage cross bar e and move the pins downward and release the webs of paper. When this occurs 95 the operator releases the handle and the extension-plate and tearing-blade automatically return therewith to their original positions or until the rear movement of shaft I is stopped by the engagement of arm j with 100 the lower end of flange k. The paper webs are then pulled out by hand until the filing holes of the next form are engaged by pegs F whereupon the withdrawn form is torn off on the tearing-blade, and the mechanism 105 of the extracting mechanism is then in position for the withdrawal of the next form.

The forward edge of arm 11 has a gage-screw 36 tapped into the same, which is locked into any position to which it may 110 be adjusted by a suitable lock-nut thereon. When arm 11 is moved forward a suitable distance, as, for instance, when it is desired to hold pegs F downward while threading the paper between the extension-plate and tearing-blade, the gage-screw will come in contact with the rear of the tension-blade and push it forward so that its upper edge 115 will not press against the underside of the paper.

If desired, the extent of the independent movement of shaft I before it imparts its movement to arm 11, can be adjusted by means of a gage-screw 37 which is tapped through the root of finger-grasp 24 in such 120 position as to be engaged by pin 30. This screw 37 may, however, be dispensed with if desired.

In order to facilitate pegs F entering the filing-holes in the paper when the latter has 130

been moved forward sufficiently to bring the holes over the same, I have sharply beveled the forward segment of the edge of the same as shown at F'; and in order to prevent the paper from meeting with an interference from the rear edge of the pegs when being drawn out of the register, I have slightly beveled the top ends of the pegs to the rear, as shown at F² in Figs. 4 and 5 of the drawings.

What I claim as new is:—

1. In an autographic register, the combination with a stationary platen over which a web of paper passes that has a longitudinally disposed series of equi-distant filing-holes therein, of a transversely elongated plate over which said web passes and which is provided with openings that are adapted to be in vertical alinement with said filing holes, said plate being movable in a horizontal plane away from and back toward the discharge end of the platen, means including pins which engage said openings and filing-holes and move said paper forward when the plate moves forward and are disengaged from said holes when said plate moves rearward.

2. In an autographic register, the combination with a stationary platen over which a web of paper passes that has a longitudinally disposed series of equi-distant filing holes therein, tension devices located below and adjacent the discharge end of said platen for resisting the rearward movement of said paper, of a transverse plate, mechanism adapted to move the same in a horizontal plane away from and back toward the discharge end of said platen, and means movable with said plate that are adapted to engage said paper and draw the same forward when said plate moves away from said platen.

3. In an autographic register, the combination with a stationary platen over which a web of paper passes having a longitudinal series of equi-distant perforations, a stationary superposed bar bridging over the discharge end of said platen, a tension-blade pivoted at its lower edge and resiliently held against said bar and resisting the rearward movement of said paper, of a transverse plate movable in a horizontal plane away from and back toward the discharge end of said platen, and means movable with said plate and engaging said web of paper and drawing the same forward when said plate moves away from said platen.

4. An autographic register comprising side-frames, a stationary platen connecting the same, a movable transverse extension-member, a longitudinally reciprocable frame supporting said member and having longitudinal parts slidably connected to said platen, mechanism which returns said frame

to its first position, and devices carried by said frame that engage the perforations of a strip of paper supported by and movable with said extension-member when said frame is moved forward and advances the 70 same.

5. An autographic register comprising side-frames, a stationary platen connecting the same, a transverse extension-plate, a longitudinally reciprocable frame supporting the same and having longitudinal members slidingly connected to said platen mechanism which returns said frame to its first position, a tearing-blade supported above and movable with said extension-plate, and devices carried by said frame that engage the perforations of a web of paper above said plate when said frame is moved forward.

6. An autographic register comprising side-frames, a stationary platen connecting the same, a transverse extension-plate, a longitudinally reciprocable frame supporting the same and having longitudinal members slidingly connected to said platen, mechanism which returns said frame to its first position, vertically movable pegs that pass through vertical holes in said extension-plate, and means carried by said frame that cause said pegs to move upward through 95 said holes and engage the perforations of a web of paper above said plate during the forward movement of said plate.

7. An autographic register comprising side-frames, a stationary platen connecting the same, a transverse extension-plate, a longitudinally reciprocable frame supporting the same and having longitudinal members slidingly connected to said platen, mechanism which returns said frame to its first 100 position, vertically disposed pegs passing through holes in said plate and penetrating a web of paper above the same, flat springs on the forward ends of which said pegs are securely mounted urging the pegs toward the paper when said frame is moved forward, and means that depress said springs and withdraw said pegs from the paper when the frame reaches the limit of its forward movement.

8. An autographic register comprising side-frames, a stationary platen connecting the same, a transverse extension-plate, a longitudinally reciprocable frame supporting the same and having longitudinal members slidingly connected to said platen, mechanism which returns said frame to its first position, vertically disposed pegs that pass through holes in said extension-plate and penetrate a web of paper above the 120 same, flat springs that are carried by said frame and on the forward ends of which said pegs are mounted, a vertically movable transverse bridge the ends of which overlie said flat springs, and means that engage said 125

bridge and move said springs and pegs downward when said frame reaches the forward limit of its movement.

9. An autographic register comprising 5 side-frames, a stationary platen connecting the same, a transverse extension-plate, a longitudinally reciprocable frame supporting the same and having longitudinal members slidingly connected to said platen, mechanism which returns said frame to its first 10 position, vertically disposed pegs that pass through holes in said extension-plate and penetrate a web of paper above the same, flat springs that are carried by said frame 15 and on the forward ends of which said pegs are mounted, a transverse bridge the ends of which engage the upper surface of said flat springs, a second set of flat springs whose rear ends are secured to the platen 20 and to the forward ends of which said bridge is secured, a longitudinally reciprocable member movable independently of said frame having a forward wedge-shaped end, and means to thrust the same in between 25 said platen and bridge when said frame reaches the limit of its forward movement and cause said pegs to release said web of paper.

10. An autographic register comprising 30 side-frames, a stationary platen connecting the same, a transverse extension-plate, a longitudinally reciprocable frame supporting the same and having longitudinal members slidingly connected to said platen, mechanism which returns said frame to its first 35 position, vertically disposed pegs thrust through holes in said plate and penetrating a web of paper above the same, flat springs upon the forward ends of which said pegs 40 are securely mounted and keep said pegs in engagement with said web of paper when said frame is moved forward, means that depress said springs and withdraw said pegs from the paper when the frame reaches the 45 limit of its forward movement, and a transverse rock-shaft having stationary bearings in said side-frames through the medium of which said supporting frame and said means are actuated.

50 11. An autographic register comprising side-frames, a stationary platen connecting the same, a transverse extension-plate, a longitudinally reciprocable frame supporting the same and having longitudinal members 55 slidingly connected to said platen, mechanism which returns said frame to its first position, vertically disposed pegs that pass through holes in said extension-plate and penetrate a superposed web of paper, flat 60 springs that are carried by said frame and on the forward ends of which said pegs are mounted, a vertically movable transverse bridge the ends of which overlap said flat springs, a second set of flat springs whose 65 rear ends are secured to the platen and the

forward ends of which support said bridge, a longitudinally reciprocable member movable independently of said frame the forward wedge-shaped end of which is adapted to be thrust in between said platen and 70 bridge when said frame reaches the limit of its forward movement and causes said pegs to release said paper, and a transverse rock-shaft journaled in stationary bearings in said side-frames and adapted to actuate 75 both said member and said frames.

12. An autographic register comprising side-frames, a stationary platen connecting the same, a transverse extension-plate, a longitudinally reciprocable frame supporting 80 said plate and having longitudinal members slidingly connected to said platen, mechanism which returns said frame to its first position, a transverse bar connecting said side-frames above the discharge end of said 85 platen, a tension-blade pivoted below the platen the upper edge of which extends up through a suitable recess in the discharge end edge of the platen and is resiliently held against said bar, devices carried by said 90 frame that are adapted to penetrate a web of paper above said plate when said frame is moved forward and advance the same and a tearing-blade supported above and movable with said extension-plate upon which said 95 paper is torn off when said plate is at the limit of its forward movement.

13. An autographic register comprising side-frames, a stationary platen connecting the same, a separate transverse plate constituting an extension of the forward edge 100 of the platen, a longitudinally reciprocable frame supporting said plate and having longitudinal members slidingly connected to said platen, mechanism which returns said 105 frame to its first position, arms secured to and depending from the same, a transverse rock-shaft journaled in bearings in said side-frames, arms projecting upward therefrom engaging said frame secured arms, 110 pegs movable vertically through holes in said plate, flat springs on the forward otherwise unattached ends of which said pegs are securely mounted, and means actuated by said rock-shaft when said supporting 115 frame reaches the limit of its forward movement that cause said springs and pegs to move downward.

14. An autographic register comprising side-frames, a stationary platen connecting 120 the same, a transverse plate constituting an extension of the forward edge of the platen, a longitudinally reciprocable frame supporting the same and having longitudinal members slidingly connected to said platen, 125 mechanism which returns said frame to its first position, stationary arms secured to and depending from the same, a transverse rock-shaft journaled in stationary bearings in said side-frames, arms projecting upward 130

- therefrom that are adapted to engage said stationary arms, pegs movable vertically through holes in said plate, flat springs on the forward unattached ends of which said 5 pegs are securely mounted, a spring supported transverse bridge the ends of which overlap said flat springs, a longitudinally reciprocal wedge, and an arm loosely mounted on said rock-shaft that is moved 10 thereby when said supporting frame reaches the limit of its forward movement, the upper end of said last mentioned arm engaging said wedge and causing it to thrust in between said bridge and platen and thereby 15 cause said flat springs and pegs to move downward.
15. An autographic register comprising side-frames, a stationary platen secured thereto, a separate transverse plate constituting an extension of the forward edge of the platen, a longitudinally reciprocal frame supporting the same, a transverse bar connecting said side-frames above the discharge end of said platen, mechanism which 20 returns said frame to its first position, a tension-blade the upper edge of which extends above the upper surface of said platen, pegs movable vertically through holes in said plate, means for moving said pegs up and 25 down including a rock-shaft, an arm projecting upward therefrom, and a gage-screw tapped into the same and adapted when said arm moves forward to engage said tension-blade and move the same substantially as 30 hereinbefore specified.
16. An autographic register comprising side-frames, a stationary platen connecting the same, a separate transverse plate constituting an extension of the forward end of 35 said platen, a longitudinally reciprocal frame supporting said plate, mechanism which returns said frame to its first position, vertically disposed pegs movable through holes in said plate and adapted to penetrate a web of paper above the same, means for moving said plate to and from 40 said platen, mechanism for moving said pegs vertically, a rock-shaft, an arm loosely mounted on said rock-shaft having one side 45 of its boss segmentally recessed, a pin projecting from said rock-shaft into said recess and adapted to impart a belated movement to said arm, said shaft and arm being adapted to actuate said devices to move said pegs
- downward after said plate reaches the limit 55 of its forward movement.
17. In an autographic register, the combination with a stationary platen over which a strip of paper passes, of a transverse member having means that engage the end of 60 said strip as it moves away from said platen, and mechanism that moves said member away from said platen a short distance and releases said strip and leaves free the forward edge thereof when it returns the said 65 member to its original position.
18. In an autographic register, the combination with a stationary platen over which a strip of paper passes, of a member adapted to be moved in a horizontal plane away from 70 the discharge end of said platen, mechanism adapted to return the member back toward said platen when said member reaches the limit of its forward movement, a superposed tearing-blade movable with said member, and means movable with said member that engages said strip of paper and draws the same forward when said member moves away from said platen. 75
19. In an autographic register, the combination with a stationary platen over which a strip of paper passes, of a member adapted to be moved in a horizontal plane away from the discharge end of said platen, mechanism adapted to return the member back toward 80 said platen when said member reaches the limit of its forward movement, and means movable with said member that engages said strip of paper and draws the same forward when said member moves away from said platen. 85
20. In an autographic register, the combination with a stationary platen over which a strip of paper passes, of a member, means for moving said member forward, devices 90 carried by said member that engage said strip of paper and draw the same forward when said member moves away from said platen, and mechanism actuated by said 95 means that release said paper when said member reaches the limit of its forward movement. 100

In witness whereof I have hereunto set my hand this 20th day of March, 1916.

ENGLAND J. BARKER.
